DESIGN FOR A FABRIC

Ruth Sacks Caplin, New York, N. Y., assignor to Kaylor Incorporated, New York, N. Y., a corporation of New York

Application August 25, 1945, Serial No. 121,628

Term of patent 14 years

(Cl. D92—1)

To all whom it may concern:

Be it known that I, Ruth Sacks Caplin, a citizen of the United States, residing at New York city, in the county of New York and State of New York, have invented a new, original, and ornamental Design for Fabric, of which the following is a specification, reference being had to the accompanying drawing, forming a part thereof.

The figure is a front view of a piece of fabric embodying my new design.

A unit of the design is contained between the broken lines. Said unit is repeated in regular succession as indicated by the extensions beyond the unit boundaries. A full width of the fabric is disclosed.

I claim:

The ornamental design for a fabric, as shown and described.

RUTH SACKS CAPLIN.
